[57] CLAIM

The ornamental design for a hood for a feeding tube or the like, as shown and described.

DESCRIPTION

FIG. 1 is a perspective view of a hood for a feeding tube or the like showing our new design;

FIG. 2 is a left side elevational view, the right side being a mirror image thereof;

FIG. 3 is a top plan view thereof;

FIG. 4 is a bottom plan view thereof; and,

FIG. 5 is a sectional view taken along line 5—5 of FIG. 3.
